Des. 203,345
Patented Dec. 28, 1965

203,345

DISPENSER FOR DISCHARGING POWDER-LIKE MATERIALS

Jordan V. Sukert, 7745 W. Davis, Morton Grove, Ill., and
Lawrence M. Sukert, 6946 N. Wolcott, Chicago, Ill.

Filed Dec. 28, 1964, Ser. No. 83,180

Term of patent 14 years

(Cl. D31—3)

FIG. 1 is a side elevational view of a dispenser for discharging powder-like materials showing our new design; FIG. 2 is plan view of the same taken looking at the top end of the device in FIG. 1; and

FIG. 3 is a plan view of the same looking at the other end of the device in FIG. 1.

We claim:

The ornamental design for a dispenser for discharging powder-like materials, substantially as shown.
